F. N. SPRAGUE

AUTOMATICALLY REVERSING RAZOR BLADE STROPPER

Filed Aug. 24, 1925

UNITED STATES PATENT OFFICE.

FRANK N. SPRAGUE, OF HOLYOKE, COLORADO.

AUTOMATICALLY-REVERSING RAZOR-BLADE STROPPER.

Application filed August 24, 1925. Serial No. 52,080.

My invention relates to automatically reversing razor blade stroppers.

The main object of the invention is to provide a device of this character comprising a handle, a strop engaging plate in slidable relation therewith, and a blade holder pivotally supported on said plate holder and so connected with the handle that the stropping movement of the handle acts to swing said blade holder on its pivots in a direction diametrically opposite to the movement of the handle, whereby the opposite sides of the blade are alternately brought into contact with the strop, anti-friction balls being interposed between the handle and the strop engaging plate, which insure an initial reverse movement of the handle at the end of each stroke before such movement is transmitted to the strop-engaging plate.

20 Further to provide resilient means which act both to cushion the engagement of the razor blade with the strop, and to lift the blade out of engagement with the strop instantly open the release of pressure on the handle at the end of each stroke thereby eliminating the possibility of cutting the strop with the blade.

These and other objects are accomplished by the invention shown in the accompanying drawings in which:

Fig. 1, is a perspective view of the improved razor blade sharpener as it appears when in use in connection with a strop and showing the anti-friction balls which are interposed between the flat end of the handle and the strop engaging plate.

Fig. 2, is a transverse sectional view of the same on the line of a pair of the ball retaining slots, the razor blade being in contact with the strop.

Fig. 3, is a transverse sectional view showing the blade holder in a position the reverse of that shown in Fig. 2, the blade being lifted out of contact with the strop under the action of its cushioning spring.

Fig. 4, is a longitudinal sectional view of the device, a portion only, of the handle being shown.

Fig. 5, is a plan view of the flat body portion of the handle.

Fig. 6, is a plan view of the strop-engaging plate.

Fig. 7, is a view of the blank from which the blade holder is formed.

Fig. 8, is an enlarged perspective view of the spring which cushions the engagement

of the blade with the strop, and which lifts the blade clear of the strop at the end of each stropping stroke.

Fig. 9, is an enlarged transverse sectional view through the pivot pin for the blade holder, and a portion of said blade holder, showing the manner of connecting the cushioning spring to the said pin and holder, and

Fig. 10, is a side view of one of the pinions which are rigidly secured to the blade holder. Referring to the accompanying drawings: The numeral 1, refers to the handle portion of the improved razor blade sharpener, which is preferably stamped from a piece of suitable sheet metal to provide the handle proper, and an extension 2, which is a continuation of one end of the handle, and is in the form of a flat plate-like member which is slightly curved from edge to edge as shown in Figures 2 and 3. A pair of parallel toothed racks 3, are formed on the plate 2, in the following manner:

A relatively long transverse slit is formed in the plate near each of its ends, and each of these slits terminates in a short slit cut at right angles to the long slit, thereby severing from the plate two strips, each of which is united to the plate along one of its long sides. The long edge of each strip is formed with rack teeth 4, and the toothed portions of the strips are then bent up at right angles to the plate as shown, the racks thus formed leaving slots 5 in the end portions of the plate, as clearly shown in Fig. 5.

The plate 2, is also provided with four short transverse slots 6, which are arranged in pairs, the slots of each pair being in end to end alignment. A pair of these slots are located near each of the racks 3, and the sides of each slot incline slightly so that the slots are slightly narrower at their bottoms than at their tops, as shown in Fig. 4.

In each slot is placed a ball 7, which is of slightly greater diameter than the narrowest portion of the slot, and therefore cannot pass through the slot, but projects slightly beyond the under side of the plate as clearly shown in Figures 2 and 4. These balls are confined in the slots 6, by a thin metal plate 8, having slots 9, corresponding in arrangement to the slots 6, the slots 9 being slightly narrower than the greatest diameter of the balls, the marginal edges of the slots 9, being slightly flared, as most clearly shown in Fig. 4, so as to better confine the balls and permit them to roll freely in their slots.

The plate 8 is secured to the plate 2, by punching projections 2^a in the plate 2 from the under side thereof, the said punch holes extending only partially through the plate; 5 and these projections enter holes 8^a in the plate 8, and the two plates are connected by applying solder at these points, or by electrical welding. This arrangement causes the slots 9 in the plate 8 to accurately register 10 with the slots 6 in the plate 2.

A strop-engaging plate 10, lies beneath the extension plate 2, and in contact with the balls 7, and is also curved to correspond with the curvature of the plate 2.

15 The plate 10, is provided with upright ears 11, which are formed by severing tongues or strips from the plate and bending them up at right angles as shown in Figures 4 and 6.

20 These ears extend up through the slots 5, in the plate 2, and are provided with bearing holes 12, in which is pivotally mounted a pin or shaft 13 upon which is secured the improved blade holder 14, which is constructed in the following manner: A plate 14^a, of the outline shown in Fig. 7, is stamped from a sheet of suitable resilient metal, and is formed with lateral extensions 16 midway of its length.

25 The extensions 16, are formed with longitudinal slots 17, and a slightly wider longitudinal slot 18, is formed centrally of the length and width of the plate. The plate 14^a is then rolled upon itself, centrally of 35 its length to form a tubular portion 19, which tightly surrounds the pin or shaft 13, and the folded portions of the plate immediately adjoining the tubular portion 19 are pressed tightly together, as shown at 20, Fig. 9 from which point they diverge for a 40 distance and then are curved toward each other, the curve terminating a short distance from the end portions of the plate which are flat and parallel and form blade 45 clamping lips 21, as clearly shown in Figures 2 and 3.

When the blank 14^a is bent or rolled upon itself to form the tubular portion 19, the slots 17 and 18 become circular slots, and the slots 17, define the position of toothed disks or pinions 22, which are mounted on the pin 13.

50 The pinions 22, as shown in Figure 10, are each provided preferably, with six teeth 55 which extend slightly more than half way around the circumference of the pinion, and with a central hole 23, and a notch or recess 24, is formed in the circumferential edge of the pinion, midway between the two end 60 teeth. The hole 23, is of the same diameter as the pin 13, but the recess 24, is of less width than the diameter of the hole 23, its width being equal to twice the thickness of the blank 14^a. Before the pin 13, is inserted 65 in the tubular portion 19, of the blade

holder, the pinions 22 are inserted in the slots 17, the folded parts 20 of the holder fitting tightly in the recesses 24 of the pinions by which the pinions are locked to the blade holder, and thus prevent the folds of 70 the holder from spreading. The ends of the tubular part 19, are then placed between the ears 11 which project up through the slots 5, of the plate 2, the opening through the tube registering with the holes 12, in 75 said ears, and the pin 13, is passed through the ears and through the tube and through the holes 23, in the pinion 22. The pin fits tightly in the tube and supports the pinions and at the same time, prevents the pinions 80 from becoming disconnected from the blade holder, the pinions being in mesh with the rack teeth 4, in the plate 2.

85 Before inserting the pin, care should be taken to arrange the parts in the positions shown in Fig. 1, or in the reverse positions or the holder should stand in a vertical position and centrally with respect to the racks 3; then when the pin is inserted the movement of the handle in either direction will 90 produce the proper swinging movement of the blade holder.

95 When the parts are assembled, the pin 13, is pivotally mounted in the ears 11, of the strop-engaging plate 10, which is not connected to the handle, but the pinions 22 bear 100 on the rack teeth 4, thus holding the plate 10, in sliding relation with respect to the handle, while the blade holder which is pivotally connected to the ears 11 of the plate 10, is thus indirectly connected to the handle.

105 A razor blade 25, is inserted between the ends 21, of the holder and is clamped between them under spring pressure exerted by the folded portions of the holder, and the blade is kept from violent contact with the strop as the blade holder swings from right to left, in the following manner: A spring S of the character shown in Fig. 8, is 110 employed which comprises a body portion 26, made up of three or more coils, the end coils terminating in oppositely projecting bowed portions 27, which terminate in U-shaped portions 28. The coiled body portion 26, lies in the slot 18, of the holder, and is mounted on the pin 13; the U-shaped end of the upper bowed portion is passed down through the straight portion of the slot 18, so that its extremity will engage 120 the under side of the folded portion 20, of the holder, as shown in Fig. 9, and the U-shaped end of the lower bowed portion 27, is likewise passed up through the straight portion of the slot 18, so that its extremity will 125 engage upper side of the said folded portions 20, of the holder, and the terminal ends of the bowed portions will then be in position to alternately engage the surface of the plate 8, as the holder swings from right 130

to left, and these terminal ends engage the said plate before the razor blade contacts with the strop, thus cushioning each swinging movement of the holder and blade and thereby preventing forcible engagement of the razor blade with the strop. The spring also prevents cutting of the strop by the blade upon each reverse stropping movement of the handle, as the pressure on the blade is released simultaneously with each initial reverse movement of the handle, thereby permitting the spring to slightly lift the blade holder and thus raise the blade out of contact with the strop. In order to eliminate the noise occasioned by the striking of the holder against the edge portion of the strop-engaging plate 10, a strip 29, of suitable resilient material, preferably rubber, is cemented to each blade-clamping lip 21, which alternately engage the edges of the plate 10, as the holder swings from one position to the other, as will be understood by reference to Figures 2 and 3.

In practice, a razor blade 25, is slipped between the clamping ends 21, of the holder and is held in place by the resilient pressure of said clamping ends. The stropper is then placed upon the strop 30, in the position shown in Fig. 1, so that the plate 10, will bear evenly upon the strop; and the stropper is then drawn back and forth over the strop in the usual manner. Upon the initial movement of the handle in either direction, the plate 10 remains stationary by frictional contact with the strop, while the rack teeth 4, on the plate portion of the handle engage and turn the pinions 22, thereby swinging the blade holder over in a direction opposite to the movement of the handle; until the blade engages the strop—its engagement with the strop being first cushioned by the spring S, as above described, after which the plate 10, moves with the handle and the blade is held in more or less forcible engagement with the strop, and at the beginning of the next stroke the blade holder is swung in a reverse direction in the manner above described, and thus the opposite sides of the blade are alternately brought into contact with the strop, as the stropper is moved back and forth over said strop.

Having described my invention, what I claim as new and desire to secure by Letters Patent is:—

1. In a razor blade stropper of the character described and which is independent of the strop, a handle having a flat extension provided with parallel slots, a strop-engaging plate beneath said flat portion having ears which extend up through said slots, and anti-friction means interposed between said latter plate and said flat extension, a blade

holder pivotally mounted in said ears, pinions rigidly connected to said blade holder, rack teeth on said flat extension which turn said pinions on the initial movement of the handle in either direction whereby the blade holder is swung in a direction opposite to the movement of the stropper, thereby causing the sides of the blade alternately to engage the strop, and means carried by the blade holder for cushioning the blade holder on either swinging movement whereby forcible striking contact of the blade with the strop is prevented.

2. In a blade stropper of the character described and which is independent of the strop; the combination with a strop-engaging plate having upright apertured ears, a handle having a flat extension provided with transverse slots through which said ears project and rack teeth adjoining said slots, a pin pivotally mounted in said ears, a blade holder rigidly connected to said pin and pinions mounted on said pin and rigidly connected with said blade holder and in mesh with said rack teeth whereby the blade holder is swung over on the initial movement of the handle in either direction, and anti-friction balls interposed between the said flat extension and the strop engaging plate; of a spring comprising a plurality of coils which surround said pin and laterally extending terminal portion which are bent around and then inward their ends engaging opposite sides of said blade holder, said laterally extending portions engaging the flat portion of said handle in the swinging movements of said holder, thereby to cushion the engagement of the blade with the strop, and to lift the blade out of engagement with the strop at the end of each stropping stroke.

3. In a blade stropper of the character described a blade holder comprising a metal plate folded centrally to form a tubular portion and blade clamping end portions, said tubular portion having a central transverse slot and a transverse slot adjacent each end, a pivot pin which passes through said tubular portion, a spring comprising coils which surround said pin and lie in said central slot, the end coils terminating in oppositely extending portions which are bent around and inward, the end of the extensions being passed in opposite directions through said slot and bent to engage the respective adjacent sides of the holder, and pinions on said pin and in the end slots of the tubular portion, said pinions having recesses in which the folded parts of the holder adjacent the tubular portion, lie, thereby holding the pinions rigid with respect to the blade holder.

In testimony whereof I affix my signature.

FRANK N. SPRAGUE.
